UNITED STATES PATENT OFFICE.

JOSEPH S. WILLIAMS, OF RIVERTON, NEW JERSEY.

RESILIENT CUSHIONING WHEEL EQUIPMENT.

1,276,149.

Specification of Letters Patent. Patented Aug. 20, 1918.

Application filed December 8, 1909, Serial No. 532,044. Renewed November 20, 1917. Serial No. 203,060.

To all whom it may concern:

Be it known that I, JOSEPH S. WILLIAMS, a citizen of the United States, residing at Riverton, Burlington county, State of New Jersey, have invented a new and useful Resilient Cushioning Wheel Equipment, of which the following is a specification.

My present invention relates to resilient tire constructions and consists of a novel resilient wheel equipment which is constructed in a novel manner and provides spacement for a novel construction and arrangement of a cushioning core, in conjunction with which is employed fluid of any desired nature, and if desired the same may be of a viscous nature.

My invention further consists of a novel construction of a transversely disposed core which is formed in such a manner as to provide for the uniform distribution of the fluid, so that the cores will have definite degrees of compressibility, both circumferentially and transversely.

It further consists of other novel features of construction all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figures 1 to 8 inclusive represent transverse cross-sections of tires, rims, and mechanisms for uniting them, embodying my invention.

Similar numerals of reference indicate corresponding parts in the figures.

Referring to the drawings:

Referring first to Figs. 1 and 2, 15 designates a rim provided with a facing 16 upon which a transversely divided annulus 17 is sprung by expansion so that the facing 16 is seated in an annular groove 18 between shoulders 19. 20 designates the outer tire casing circumferentially split at 21, and provided with annular ribs or terminals 22 seat-

ed in corresponding grooves 23 of the annulus 17, and supported and stiffened by reinforcing strips 24. 25 designates a tread of any desired nature, which is reinforced by strips of fiber or other material 26, preferably located as illustrated. The cushioning core is adapted to receive compressible fluid, and is provided with a solid portion having ribs, ridges or projections capable of carrying the load in case of relapse of the inner tube, 27, it being understood that all of the constructions illustrated are designed to be provided with means for inflation, one type of such means being shown in Fig. 4.

28 designates the solid cushion having annular ribs, such cushion being shown in Fig. 1 on the inner periphery of the inner tube 27, while in Fig. 2 the same is shown at the outer periphery, and the inner periphery of the spacement within the inner tube is provided with transverse ribs 29, and the construction seen in Fig. 2 may be employed either with or without fluid pressure in the inner tube. The outer casing 20 in Fig. 2, is provided with terminal flanges 30 preferably having reinforcements 31 and supported by a removable annular seating and rim member 32. The parts are held in place by interlocking clamping rings 33 and 34, one of which is provided with an annular rib 35 interlocking with the corresponding depression in the tire facing 36 of the rim 15.

37 designates radial bolts. The valve illustrated in Fig. 4 comprises an outer member 38 adapted to remain with the tire part and carries a check valve, and also an inner valve member 39 detachable from the member 38. The lining 27 in Fig. 4 may be an inner tube or represent the inner portion of a core whose remaining parts 40 are not shown in detail, and if such was used it would preferably be provided with stiffening and strengthening material in a similar manner to the core 32 seen in Fig. 2. If an inner tube is used, strips of more flexible and resilient material may be employed if desired, about the tube, preferably at the lateral extremities, as at 41.

In the embodiment seen in Fig. 5 the rim and its adjuncts are of the well known Marsh type, employing clunker rings 42, a tire band 43 and split locking rings 44. The outer casing has abutments 45 com-

pressed together initially before the locking mechanism is applied.

In the embodiment seen in Fig. 6, the rim is shown with an annular channel 46, within 5 which a split ring 47 is compressed, after it has been placed on the tire 48 so that the reinforced portions 49 are secured within the interlocking recesses 50. The lips 51 of the ring 47 are of greater diameter than the 10 reinforcing strips 52 in order to provide greater stability and prevent dislodgment due to cutting or stretching.

53 designates cavities for lightening the construction and increasing resiliency. The 15 tire 48 may be a single tube or may be split at one or more points as at 54, with inserts to complete the construction and form support for the compressible members 55 and 56, and the space 57 may receive fluid under 20 pressure, if desired, and either of the members 55 or 56 may be omitted if desired.

In the embodiment seen in Fig. 7, 58 25 designates clamping members having fastening devices 59, which clamp a terminal 60 in position, such terminals being reinforced at 61, and adapted to interlock with the clamping members so that such terminals are compressed against an intermediate annular support 62, which receives the pressure 30 transmitted from the tread portion 63. 64 designates reinforcing layers of fabric. The cushion core in this embodiment, comprises a plurality of layers of annular ribs 65, interspersed by transverse ribs 66, passages 67 35 being provided between them to provide for the free passage of fluid. These layers 65 may be independent or united and as shown I employ two oppositely facing strips each having circumferential ribs on one side and 40 transverse ribs on the other, the transverse ribs being placed toward each other and having placed between these two strips a third strip, having both sides formed with annular ribs.

45 In the embodiment seen in Fig. 8, the rim construction differs from the Marsh type, in that the rim member 43' terminates laterally in a gutter 68 coöperating with a locking ring 69, and also in the fact that the annular 50 rings 42 are initially compressed before the locking mechanism is put in use against the terminals 60' and the supporting edges 70 of the rings 42 are extended to form a broader seat and support for the tire.

55 71 designates a filler and core between the tire terminals, which is prevented from creeping by means of bolts 72, and the compression of the terminals against such core. The cushion core employed comprises upper 60 and lower circumferential ribs 28, with intermediately oppositely placed transverse ribs 73, which vary in depth from their edges to their highest points at the center. Fluid pressure is preferably employed in

this type which may have free passage 65 through the apertured body portion of the ribs 73.

The spacements or apertured parts of the different types of cushion cores shown, can be filled with any suitable gas, fluid, viscous 70 or mobile material, or with a material which will solidify after insertion in the core and provide the requisite elasticity and mobility, and any desired pressure may be employed.

It will be seen that, with the exception of 75 the spacement or channels 57 seen in Fig. 6, the fluid in all the embodiments shown has free communication, and the air is not trapped locally as in my co-pending application, filed December 8th, 1909, Serial No. 80 532,045. In all the embodiments of my invention, the inner portion of the wheel equipment is circumferentially inextensible, and the fabric or other reinforcements exterior of the cushion core render such portion circumferentially inextensible, so that 85 the cushion core is located between two circumferentially inextensible fields.

It will be seen that the outer casing has a tension belt crossing vertical planes of the 90 construction outwardly of the major transverse axis of the construction with flattened arch formation substantially throughout the width of the tread bearing surface with curvatures at the sides to terminal seatings. 95

The core is in constant supporting relationship with the inner walls of the casing and has an annularly and transversely arranged channel in which is located a cellular construction. The annular body, inwardly of the core space, is provided with means to secure circumferential inextensibility and means are provided to secure the core and casing in constant coöperative relationship. 100

It will now be apparent that I have devised a novel and useful construction of a resilient cushioning wheel equipment which embodies the features of advantage enumerated as desirable in the statement of the 110 invention and the above description, and while I have, in the present instance, shown and described preferred embodiments thereof, of which in practice will give satisfactory and reliable results, it is to be understood 115 that the same are susceptible of modification in various particulars without departing from the spirit or scope of the invention or sacrificing any of its advantages.

Having thus described my invention, what 120 I claim as new and desire to secure by Letters Patent, is:—

1. A resilient tire, comprising an inner support, an annular and transversely elongated tension belt having flattened formation across the median line and in spaced relationship about said support with curvatures about the sides to terminal seatings, 125

and an annular and transversely elongated resilient core engaging the inner walls of the outer casing and in constant supporting relationship therewith, inwardly and outwardly of the major transverse axis, and provided with annularly and transversely disposed channels forming cellular construction, providing space for definite ranges of resilient movements of the belt and core and resilient non-collapsible support for load about said inner support.

2. A resilient tire, comprising an inner support, an annular and transversely elongated tension belt having flattened formation across the median line and in spaced relationship about said support with curvatures about the sides to terminal seatings, and an annular and transversely elongated resilient core engaging the inner walls of the outer casing and in constant supporting relationship therewith, inwardly and outwardly of the major transverse axis, and provided with annularly and transversely disposed channels forming cellular construction, providing space for definite ranges of resilient movements of the belt and core and resilient non-collapsible support for load about said inner support, and mobile contents under pressure in said core.

3. A resilient tire, comprising an inner support, an annular and transversely elongated tension belt having flattened formation across the median line and in spaced relationship about said support with curvatures about the sides to terminal seatings, and an annular and transversely elongated resilient core engaging the inner walls of the outer casing and in constant supporting relationship therewith, inwardly and outwardly of the major transverse axis, and provided with annularly and transversely disposed channels forming cellular construction, providing space for definite ranges of resilient movements of the belt and core and resilient non-collapsible support for load about said inner support, and means to vary the tension of said tension belt and core.

4. A resilient tire, comprising an inner support, an annular and transversely elongated tension belt having flattened formation across the median line and in spaced relationship about said support with curvatures about the sides to terminal seatings, and an annular and transversely elongated resilient core of elliptical formation engaging the inner walls of the outer casing and in constant supporting relationship therewith, inwardly and outwardly of the major transverse axis, and provided with annularly and transversely disposed channels forming cellular construction, providing space for definite ranges of resilient movements of the belt and core and resilient non-collapsible support for load about said inner support.

5. A tire, comprising an annular, transversely elongated resilient body having its tread portion lying within a circle formed by a radius of one-half the major transverse axis of the tire and having tensile reinforcements located on opposite sides of such axis and extending transversely of the tire in flattened formation across the median line with curvatures at the sides to inner peripheral seatings, in combination with an annular and transversely elongated resilient core engaging the inner walls of the outer casing and in constant supporting relationship therewith inwardly and outwardly of the major transverse axis and provided with annularly and transversely disposed channels forming cellular construction, providing space for definite ranges of resilient movements of the reinforcements and core and resilient non-collapsible support for load about said inner support.

6. A tire, comprising an annular, transversely elongated resilient body having its tread portion lying within a circle formed by a radius of one-half the major transverse axis of the tire and having tensile reinforcements located on opposite sides of such axis and extending transversely of the tire in flattened formation across the median line with curvatures at the sides to inner peripheral seatings, in combination with an annular and transversely elongated resilient core engaging the inner walls of the reinforcements and in constant supporting relationship therewith inwardly and outwardly of the major transverse axis and provided with annularly and transversely disposed channels forming cellular construction, providing space for definite ranges of resilient movements of the reinforcements and core and resilient non-collapsible support for load about said inner support so as to provide definite ranges of resilient movements radially and along the plane of road contact of the tire.

7. A resilient tire, comprising an inner support, an annularly and transversely disposed tension belt extending with curvatures about the side to said inner support, a thread outwardly of said tension belt in spaced relationship about said support and with flattened formation across the median line, an annular and transversely elongated resilient core between the belt and support and provided with annularly and transversely disposed channels forming cellular construction, and providing space for definite ranges of resilient movements about said inner support and along the plane of road contact with slight variation in ranges of resilient altitude with and without mobile contents under pressure in said core.

8. A tire, comprising an inner support, an annular and transversely disposed tension

member with curvatures at the sides to said inner support and with flattened formation between the sides, and an annularly and transversely disposed resilient core provided with annularly and transversely disposed channels forming cellular construction in tension and in spaced non-collapsible rela-

tionship about said support providing definite ranges of resilient flexing of said member under load.
